(57) **CLAIM**

The ornamental design for a rotatable handle for electric vehicle, as shown and described.

DESCRIPTION

FIG. 1 is a perspective view of our new design for a rotatable handle for electric vehicle, showing an illustration of use on an electric vehicle;

FIG. 2 is another perspective view thereof, shown in an alternative position of use on an electric vehicle;

FIG. 3 is a top, front, and left side perspective view thereof, with the exemplary electric vehicle removed for clarity of details;

FIG. 4 is a bottom, rear, and right side perspective view thereof;

FIG. 5 is a front view thereof;

FIG. 6 is a rear view thereof;

FIG. 7 is an enlarged right side view thereof;

FIG. 8 is an enlarged left side view thereof;

FIG. 9 is a top view thereof; and,

FIG. 10 is a bottom view thereof.

The broken lines shown in the drawings are for the purpose of illustrating environmental subject matter and portions of the article that form no part of the claimed design. The dash-dot broken lines represent the bounds of the claim. None of the broken lines form a part of the claimed design. The shading lines shown in the drawings represent the approximate three-dimensional contour of the design, and are not intended to indicate surface decoration.
